(54) **STONE, SAW MILL**

(76) Inventor: **Daniel Bunnel**

*Daniel Burnel Xenia, Ohio
Letters Patent*

The Schedule referred to in these Letters Patent and making part of the same containing a description in the words of the said Daniel Burnel himself of his improvement in the mill for sawing stone,

To all to whom these presents shall come:--Be it known that I Daniel Burnel of Xenia in the County of Greene and State of Ohio, have invented a new and useful machine for cutting Stone and the following is a full and exact description thereof, to wit: 1st A shaft made of iron or other material the thickness and length of which must depend upon the number of bars and horse head, with offsets or collars to draw the carriage by means of pitmen, having joints at each end. 2nd The carriage frame to be of wood 6 by 2 inches square 10 feet long more or less, as the stone may require, and 3 feet in width with four posts, 2 feet 6 inches high, 6 by 6 inches square with 1 brace at each post. The top railately 1 $\frac{1}{2}$ by 3 inches width, a space with a half an inch between the two rails above and the two rails below through which may be called belt, go to be confined by screws or other means, to gauge one or more bars nothing more with 4 wheels of iron or other material supporting the carriage and running on a rail way. 3rd The length of the carriage in proportion to the carriage. The height 4 feet more or less, as the thickness of the stone may require with a brace in the middle and rod of iron at the top by which the saw made of soft iron is strained by a screw or other means. In testimony whereof I have hereunto set my hand this eighth day of August in the year of our Lord One thousand eight hundred and thirty five
